UNITED STATES PATENT OFFICE.

DAVID M. MOTHERWELL, OF CHICAGO, ILLINOIS, ASSIGNOR TO THE WHITMAN & BARNES MANUFACTURING CO., OF AKRON, OHIO, A CORPORATION OF OHIO.

TRAVELING CARRIER.

No. 845,884.

Specification of Letters Patent.

Patented March 5, 1907.

Application filed April 23, 1906. Serial No. 313,248.

To all whom it may concern:

Be it known that I, DAVID M. MOTHERWELL, a citizen of the United States, residing at Chicago, in the county of Cook and State of Illinois, have invented certain new and useful Improvements in Traveling Carriers, of which the following is a specification, reference being had therein to the accompanying drawings.

- My invention relates to traveling carriers which operate to raise a load vertically, convey it horizontally supported from an overhead way, and release it at a desired point.

The object of the invention is to provide a carrier which may be locked on the overhead stop while the load is secured in a sling or other convenient attaching device, hoisted, tripped at any desired elevation in such a manner that the suspending-rope is grasped 20 with a force approximately equal to the entire weight of the load, and, thus suspended, conveyed to the unloading-point, where the sling or attaching device is operated to release the load, the carrier being then swiveled 25 about and drawn back to the loading-point onto the stop which operates the tripping mechanism and unfastens the suspending-rope and sling, permitting them to be lowered in proper position for taking on a new 30 load.

The invention provides means by which the load is released with its length at right angles to the path of travel thereof, thereby saving labor in pitching or shifting the loads 35 after release, and it also provides a trip-lever which may be set up on the track at any point and which is controlled by a guide-rope independently of the carrier.

My invention also provides means for 40 holding the car firmly in the stop, and it contemplates a compact, safe, durable, and economical construction of the parts.

In general my device comprises, in connection with an overhead track, a stop and carriage, a lower swivel-frame, and an inner tripping-frame carrying the pulleys upon which the sling or other attaching device is secured.

In the accompanying drawings, wherein 50 like letters and numbers refer to similar parts throughout the several figures, I have shown a device embodying my invention.

Figure 1 is a side elevation of the hay-carrier suspended upon a section of track. Fig.

2 is an end elevation of the same, taken on line 2 of Fig. 1, showing the track in transverse section. Fig. 3 is an enlarged longitudinal sectional view of the car, taken on line 3 of Fig. 2. Fig. 4 is a plan sectional view of the pivotal section of the car, taken on line 4 of Fig. 5, the same being shown as detached or independent of the traveling portion of the car. Fig. 5 is a transverse sectional view of the car, taken on line 5 of Fig. 1. Fig. 6 is a sectional end view on line 6 of Fig. 3.

In the drawings, A indicates the main truck or carriage, B the outer swivel-frame, and C the inner tripping-frame, which turns with the swivel-frame B, but drops and rises 70 within it as the tripping device and locking-dog are operated. As a matter of convenience in construction I prefer to make the carriage A and frames B and C in halves or sections. A comprises the sections A' A², 75 bolted together at the points 77. This carriage is provided with the truck-frames 8, to the upper corners of which are secured in the usual manner trucks or wheels 9, adapted to run on flanges 10 of overhead track 11 and 80 support the carrier. The carriage A bears on its lower extremity the two halves of the circular swivel-collar 12, in which reversible gripping-frame B is supported by means of circular guide-flange 13, adapted to turn 85 freely in channel 14 of collar 12. Frame B I prefer to construct in two parts B' B², bolted together at the points 15 15. Supported by B' B² is the movable inner sheave-frame C, likewise preferably constructed in 90 two parts C' and C² and bolted together at the points 16 16 and also by bolts 17, which form an axle for pulleys 18 and 19 thus carried by the frame C. C' is provided with lateral projections 20 and 21, extending outwardly in the direction of draft, between 95 which, carried on bolt 22 as an axle, is idler or guide pulley 23, the projections 20 and 21 being placed at an angle to the horizontal, so that pulley 23 dips in the direction of pulley 18. This pulley serves as a support for the draft or suspending rope R in turning at right angles in the frame, both in the free and locked position of the rope. This construction enables me to support the load so that 100 its long way is carried at approximately right angles to the direction of draft and delivered in this position. It also prevents the rope

105

from burning or rubbing, and thus damaging or wearing out the parts and causing the mechanism to stick or stall.

On the frame B are provided projecting 5 supporting-arms 25 and 26, extending in the direction of draft, and bolted thereto at 29 and 30 is a gripping-bracket 27, upon the outward end of which are placed suitable vertical guide-spools 31 and 32 on vertical 10 axles 33 and 34, bound together at the top by a strap 35 riveted to the axles. Secured to the lower inside end of bracket 27 or cast integral therewith is a supporting-brace 36, carried around from the horizontal to the 15 vertical to bear against the central side portion of frame C. On the end adjacent to frame C is a vertical guideway 37, and upon the surface of the frame C is a vertical ear-lug 38, adapted to constantly engage and 20 move freely up and down in the channel 37, thus preventing the frame C from swinging out of vertical alinement. I prefer to cast this lug integral with the frame C.

The bars A' and A² of the carriage A are 25 provided with oppositely-disposed ways or guides 39 and 40, adapted to prevent central locking-dog 41 from moving out of the vertical. Central locking-dog 41 is provided 30 with side arms 42 and 43, adapted to move up and down in the ways 39 and 40, and it comprises besides the arms described a shank having a head 44 adapted to be engaged by and raised in ways 45 and 46 of stop S on the overhead track 11. To the lower portion of 35 this shank is secured by bolt 48 a collar 48^a, provided with an annular groove 48^b, engaging an annular flange 47 within frame C, thus making a swivel connection between dog 41 and frame C. Thus dog 41 has only 40 vertical movement within the carriage A, but is secured to and moved with the frame C in its vertical movement, but not in its swivel movement.

Projecting from the frame B in the direction opposite to that of draft is a bracket 49, to which is fulcrumed at the point 50 a lever 51, passing through a recess opening in frame C. Lever 51 is pivoted within the recess 52 to the two halves C' and C² of the 55 frame C at the points 53 and moves with the latter. On the opposite end of lever 51 is pivoted at 54 a movable and swinging rope-clamp member 55, so arranged that it is suspended directly above bracket 27, which forms the stationary member of the 60 rope-clutch. Clamp 55 and bracket 27 have crimps or corrugations between which the rope is grasped and securely held. Lever 51 is so inclined that as the recesses 45 and 46 65 in the stop S engage the head 44 lever 51 rises with the frame C, turning on the point 50, and draws the clamp 55 away from the draft-rope, and likewise when head 44 is released from the ways in stop S lever 51, 70 falling with the frame C turning on the point

50, draws clamp 55 in contact with the draft-rope to firmly engage it on bracket 27. As shown in the drawings, the crimps on bracket 27 and clamp 55 are oppositely-disposed intermeshing crimps adapted to form a 75 clutch.

Pivoted at the point 57 to extending arm 58, attached to frame B' at the point 59, is the compound tripping-yoke D. This yoke extends beneath the car and is carried around and upward at the other end to the point 60, where it is pivoted at the point 60 to the link 61, which in turn is pivoted at the point 62 to tripping member 63, pivoted at 15 to the frame B'. The free or upper end of tripping member 63 extends within the part A of the hay-carrier, where it encircles the swivel-collar 47 of the frame C. This provides a swivel-ring 64, so that the parts just described may turn or swivel with the 80 frame B. Pivoted to B' at the point 66 is the compound lever L, which consists of the link 65, pivoted at 67 to B', and the tripping-dog or crank member 68, pivoted to B' at 66 and to link 65 at the point 69. The outer end of the lever L is extended and pivoted to D at the point 70.

In order to trip the load at any desired elevation, I provide near the stop S the hand-trip T, which consists of upright arms 71 and 72, bolted on the central or web portion of the overhead track 11. These central arms carry an axle 73, on which is pivotally mounted a lever 74, carrying at one end a suitable eye 75 for the attachment of a rope or hand-cord, and a contacting surface 76 at the opposite end, adapted to thrust the plunger 77 downward. Plunger 77 is carried in a vertical guide 78, its lower end resting upon the tripping-ring 64. By raising the end 75 of lever 74 the surface 76 thrusts the plunger 77 downward against tripping-ring 64, causing the trip member 63 to turn on its pivot 15 and draw the lever D to the position shown in dotted lines in Fig. 6.

Within the frame B² is a vertical way or channel 79, adapted to receive the lug or guide 80. This lug or guide is preferably cast integral with the frame C, and the channel and lug are placed directly over the member 81 of dog 68. It will thus be seen that by operating the lever L to turn bell-crank 68 on its pivot 66 that frame C may be alternately held in elevated position and lowered within the frame B. In the position shown in solid lines in Fig. 6 the frame C is held in its elevated position; but when the tripping-lever D is thrust into the position indicated by dotted lines in the same figure the member 81 is swung out from under the lug 80, so that the frame C drops, carrying with it lever 51 and gripping the draft-rope in the clutch.

The operation of my device is as follows: The stop S is secured to the overhead track at the point most convenient for loading.

The rope R is then carried over the pulley 19 and at the lower end secured to an eye 83 in block-pulley P. The other end is then brought through pulleys P P', then over pulley 18, over idler 23 between spools 31 and 32, and connected with power. The carrier is then mounted on the overhead track, and the central locking-dog raises the frame C as the head 44 slips into the inclined ways 45 and 46. The tripping member is then thrown into the position shown in solid lines in Fig. 6, the dog 68 supporting the frame C by means of member 81 and lug 80. The load is then attached in the well-known manner to the hooks on pulleys P and P'. In my device it is not necessary that the pulleys P and P' should be elevated to such a height as to contact with the lever D and free the carrier from the stop. In order to save unnecessary labor, it is only necessary that the load should be elevated to a height desired to clear the ground. As soon as this height is attained the carrier may be freed from the stop and the load locked in position by bringing lever 74 down into contact with plunger 77, thereby causing the plunger to depress the collar 64 and elevate the member 63, thereby causing the lever D to turn upon the pivot 57, raising end 65 of lever L to operate crank member 68 and draw member 81 from under the supporting-lug 80. The weight of the load itself causes the entire frame C to fall, carrying with it lever 51 and causing dog 55 to bite the rope between its under surface and the bracket 27. The rope is thus grasped and firmly held by the entire weight of the load. The hay-carrier is then drawn, by means of the rope R; in the direction indicated by the arrow a in Fig. 3, and the car is brought to the unloading-point. The load is then released from the sling in the usual manner and the car is drawn back toward the stop S, where the inclined ways 45 and 46 grasp the head 44 of the central tripping-dog 45 and lift the frame C, thus raising lever 51 and releasing the rope from the clutch or clamp 55 and bracket 27.

It will be apparent from the foregoing that the tripping may be accomplished either by means of the device T or by the frame of the pulleys P and P' contacting with the lever D directly. In the latter case the freeing of the load is the same, the use of the tripping device T and plunger 77 being unnecessary. This method of tripping may be most conveniently used in building the top of a stack.

To prevent the end of the car nearest the draft from raising off the track, I have provided the stop S with longitudinal grooves or channels 85 and 86 and the parts A' and A² with oppositely-disposed lugs 87 and 88, adapted to engage or run within these channels.

While I have described this particular embodiment of my invention in detail, I realize

that there are considerable variations in details of construction which may readily be made by persons skilled in the art without departing from the spirit of my invention, and I therefore do not limit myself to the particular form except as set forth in the claims.

Having thus described my invention, what I claim, and desire to secure by Letters Patent, is—

1. In combination with a carriage adapted to travel on a horizontal overhead way, a dog adapted to move in vertical guides in said carriage, a stop on said way having inclined surfaces adapted alternately to raise said dog and to permit it to drop, an outer frame suspended from and swiveled to said carriage, an inner frame swiveled to said dog and adapted to turn with said outer frame, a clamp comprising a stationary member rigidly supported on said outer frame, a movable member pivoted to one end of a lever, a lever pivotally attached intermediate of its ends within said inner frame, fulcrumed at one end to said outer frame and attached at the other to said movable clamp member, a dog and lever adapted alternately to engage said inner frame and hold it in elevated position and to release it to fall within said outer frame to lock said clamp, and means for attaching a load to said inner frame, for the purposes described.

2. In a carrier adapted to be drawn along an overhead way, an outer frame, an inner frame vertically movable therein, a lever pivoted at one end to said outer frame at the other to the movable member of a rope-clamp and intermediate thereof to said inner frame, said lever extending in the direction of draft of said carrier and being adapted to support said inner frame in lowered position, a rope-clamp comprising a rigid member secured to said outer frame and a movable member pivoted to said lever and adapted to move with said inner frame, and rope-supporting pulleys mounted upon said inner frame, to turn in planes at approximately right angles to the direction of draft of said carrier.

3. In combination with a truck-carriage adapted to travel on a horizontal overhead way, a dog adapted to move in vertical guides in said carriage and elevate an inner frame, a stop on said way adapted alternately to raise and drop said dog, an outer frame swiveled to said truck-carriage, an inner frame swiveled to said dog and adapted to turn with said outer frame, a rope-clamp comprising a stationary member rigidly supported on said outer frame, and a movable member pivoted to one end of a lever, a lever attached intermediate of its ends to said inner frame, fulcrumed at one end to said outer frame and pivoted at the other to said movable clamp member, a crank member adapted to hold said inner frame in elevated position, a trip-lever and link adapted to rock

4. said crank member and drop said frame, and a collar, embracing said dog, having a lever secured thereto pivoted to the outer frame and linked to said trip-lever and adapted to operate the same to rock said crank member when said dog and inner frame are raised by said stop.

5. In a carrier adapted to travel upon an overhead way, a truck-carriage, an outer frame, an inner frame therein carrying supporting-pulleys, a clamp comprising a rigid member upon said outer frame and a movable member secured to one end of a lever, a lever pivoted at one end to said outer frame and to said inner frame intermediate of its ends, a crank member adapted to support said inner frame in elevated position, a tripping-lever and link adapted to operate said crank member to alternately drop said inner frame into lowered position and support it in elevated position, a vertical movable dog swiveled to said inner frame, a collar embracing said dog having a lever end pivoted to said outer frame and a link connection with said tripping-lever, whereby elevating said dog lifts said inner frame and throws said crank member in position to support it and operation of said tripping-lever rocks said crank member from beneath said inner frame, substantially as described.

35. In a hay-carrier adapted to travel on an overhead way, supporting-pulleys and a rope-clamp on said carrier, a rope and pulley-block, said clamp projecting in the direction of draft of said carrier and said supporting-pulleys being set to turn at approximately right angles thereto, tripping mechanism adapted to be operated by contact with said pulley-block for locking said clamp, a tripping device on said way adapted to operate said tripping mechanism to lock said clamp independently of said pulley-block and means for unlocking said clamp, substantially as described.

40. 6. In a hay-carrier, an outer frame, an in-

ner frame vertically movable therein, a trip-lever operated by impact from below the carrier, a collar embracing a tripping-dog and having a lever end pivoted to said outer frame and link connections to said trip-lever, 50 a tripping device adapted to operate said trip-lever from above through said lever end and link connections, a vertically-movable dog swiveled to said inner frame and adapted, when raised, to draw up said inner frame, a 55 link from said trip-lever to a crank member, and a crank member adapted to be alternately rocked by said trip-lever beneath said inner frame to support the same and away from it to allow said inner frame to drop, whereby said inner frame may be dropped by impact from below the carrier or by said tripping devices, and lifted and locked in elevated position by raising said dog.

7. In combination with a track having a stop thereon adapted to engage and lift the tripping-dog of a hay-carrier, a hay-carrier on said track having an outer frame and an inner load-supporting frame vertically movable therein, a tripping-dog vertically movable in 70 said outer frame and swiveled to said inner frame, a trip-lever D operable by impact from below the carrier, a link L secured to one end of said lever D and to the free end of a crank member, a crank member pivoted on 75 said outer frame in position to be swung alternately under said inner frame to support the same, or away from it to permit it to drop, and a collar about said dog having a lever end pivoted on said outer frame and linked to the free end of the lever D, adapted to rock said crank member when said dog and inner frame are raised by engagement with said stop.

80. In testimony whereof I hereunto affix my signature in presence of two witnesses.

DAVID M. MOTHERWELL.
